LIQUID DISCHARGE HEAD

CROSS REFERENCE TO RELATED APPLICATIONS

The present application claims priority from Japanese Patent Application No. 2020-179934, filed on Oct. 27, 2020, the disclosure of which is incorporated herein by reference in its entirety.

BACKGROUND

There is a known configuration which is provided with a supply manifold and a return manifold and in which an ink is circulated between an ink tank and a liquid discharge head, with suppression of increase in the viscosity of the ink inside a nozzle as a purpose of the configuration.

A conventionally known liquid discharge head has a bypass channel communicating a supply manifold and a return manifold configured to have a two-story structure with each other. Owing to such a configuration, air can be exhausted from a downstream end of the supply manifold to the return manifold. Such a bypass channel is arranged to be away from each of individual channels, and includes a part extending from the downstream end of the supply manifold on an extension line of the supply manifold, and a part communicating the supply manifold and the return manifold with each other.

SUMMARY

However, there is such a fear that in a case that the bypass channel is constructed of a plurality of etching plates, any deviation in adhering the plurality of etching plates might cause the channel resistance in the bypass channel to change, which in turn might lead to such a situation that the ink cannot be made to flow in a desired flow amount.

In view of the situation as described above, an object of the present disclosure is to provide a liquid discharge head capable of allowing the liquid to flow from the supply manifold toward the return manifold in a desired flow amount, even in a case that any deviation in the adhesion among the plurality of plates occurs.

A liquid discharge head according to an aspect of the present disclosure includes: a plurality of first individual channels; a first supply manifold; a first return manifold; a plurality of second individual channels; a second supply manifold; a second return manifold; and a first bypass channel. Each of the plurality of first individual channels includes a first nozzle. The first supply manifold is connected to the plurality of first individual channels and is configured to supply a liquid to the plurality of first individual channels. The first return manifold is connected to the plurality of first individual channels and is configured to cause the liquid not discharged from the first nozzle to flow therein. Each of the plurality of second individual channels includes a second nozzle. The second supply manifold is connected to the plurality of second individual channels and is configured to supply the liquid to the plurality of second individual channels. The second return manifold is connected to the plurality of second individual channels and is configured to cause the liquid not discharged from the second nozzle to flow therein. The first bypass channel communicates the first supply manifold and the second return manifold. The first bypass channel includes: a first supply connecting channel connected to the first supply manifold, a first return connecting channel connected to the

2

second return manifold, and a first connecting channel communicating the first supply connecting channel and the first return connecting channel. Channel resistance in one of the first supply connecting channel and the first return connecting channel is greater than channel resistance in the first connecting channel.

The channel resistance in one of the first supply connecting channel and the first return connecting channel is greater than the channel resistance in the first connecting channel.

10 Accordingly, it is possible to make the difference in the channel resistance in the entirety of the first bypass channel to be substantially absent, even in a case that any deviation in the adhesion among the plates occurs and that a part of the first connecting channel is clogged. With this, it is possible to allow the liquid to flow from the supply manifold toward the return manifold in the desired flow amount.

15 With this, it is possible to provide a liquid discharge head capable of allowing the liquid to flow from the supply manifold toward the return manifold in a desired flow amount, even in a case that any deviation in the adhesion among the plurality of plates occurs.

BRIEF DESCRIPTION OF THE DRAWINGS

25 FIG. 1 is a view schematically depicting the overall configuration of a liquid discharge apparatus.

FIG. 2 is a schematic view depicting the overall configuration of the liquid discharge apparatus, as seen in a plane view from thereabove.

30 FIG. 3A is a schematic view depicting the plane configuration of the liquid discharge head, and FIG. 3B is a schematic view depicting the cross-sectional structure of the liquid discharge head.

FIG. 4 is a cross-sectional view depicting a part of 35 constituent components of a first bypass channel.

FIG. 5 is a cross-sectional view depicting a part of constituent components of a second bypass channel.

FIG. 6 is a plane view depicting arrangement of a first supply manifold, a first return manifold, a second supply 40 manifold, a second return manifold, the first bypass channel and the second bypass channel.

FIG. 7 is an exploded perspective view depicting the configuration of each of the first bypass channel and the second bypass channel.

45 FIG. 8 is a perspective view depicting the configuration of another liquid discharge head.

DETAILED DESCRIPTION

50 In the following, a liquid discharge head of the present disclosure will be explained, with reference to the drawings. The liquid discharge head explained in the following is merely an embodiment of the present disclosure. Accordingly, the present disclosure is not limited to or restricted by 55 the following embodiment; any addition, deletion and/or change are/is possible within the range not departing from the gist and spirit of the present disclosure.

<Configuration of Liquid Discharge Apparatus>

As depicted in FIG. 1, a liquid discharge apparatus 1 60 includes a paper feed tray 10, a platen 11 and a line head 12 which are arranged in this order from below. The paper feed tray 10 accommodates a plurality of pieces of a sheet P. The platen 11 which is long in an orthogonal direction orthogonal to the sheet surface of FIG. 1 is provided at a location 65 above the paper feed tray 10. The platen 11 is a plate-shaped member and supports the sheet P, which is being conveyed, from therebelow. The line head 12 is provided further at a

location above the platen 11. A plurality of liquid discharge heads 13 are provided on the line head 12. Further, a paper discharge tray 14 is provided at a location in front of the platen 11; the paper discharge tray 14 receives the sheet P after recording has been performed thereon.

A sheet conveying route 20 is extended from a location on the rear side of the paper feed tray 10. The sheet conveying route 20 links or connects the paper feed tray 10 to the paper discharge tray 14. The sheet conveying route 20 can be divided into three paths which are: a curved path 21, a straight path 22 and an end path 23. The curved path 21 is curved upward from the paper feed tray 10, and reaches to the vicinity of a rear side of the platen 11. The straight path 22 extends from an end point of the curved path 21 and reaches to the vicinity of front side of the platen 11. The end path 23 extends from an end point of the straight path 22 and reaches up to the paper discharge tray 14.

The liquid discharge apparatus 1 is provided with, as a conveyer configures to convey the sheet P, a feeding roller 30, a conveying roller 31 and a discharging roller 34. The conveyer conveys the sheet P in the paper feed tray 10 up to the paper discharge tray 14 along the sheet conveying route 20.

Specifically, the feeding roller 30 is provided at a location above the paper feed tray 10 and makes contact with the sheet P from thereabove. The conveying roller 31 is combined with a pinch roller 32 to thereby construct a conveying roller part 33, and is arranged in the vicinity of a downstream end of the curved path 21. The conveying roller part 33 links or connects the curved path 21 and the straight path 22. The discharging roller 34 is combined with a spur roller 35 to thereby construct a discharging roller part 36, and is arranged in the vicinity of a downstream end of the straight path 22. The discharging roller part 36 links or connects the straight path 22 and the end path 23.

Here, the sheet P is supplied to the conveying roller part 33 by the feeding roller 30 via the curved path 21. Further, the sheet P is fed from the straight path 22 to the discharging roller part 36 by the conveying roller part 33. In the straight path 22, a liquid such as an ink, etc., is discharged or ejected from the liquid discharge heads 13 with respect to the sheet P on the platen 11. An image is recorded on the sheet P. The sheet P on which the recording has been performed is conveyed by the discharging roller part 36 up to the paper discharge tray 14.

As depicted in FIG. 2, the line head 12 has a lower surface which faces or is opposite to the sheet P, and has a length not less than a length of the sheet P, in a direction (orthogonal direction) orthogonal to a direction (conveying direction) in which the sheet P is conveyed. The above-described lower surface is a nozzle surface provided with nozzles 57 each of which is included in one of a plurality of individual channels 100 (FIGS. 3A and 3B to be described later on).

A tank 16 is connected to each of the nozzles 57. The tank 16 includes a sub tank 16b arranged on the line head 12 and a storing tank 16a connected to the sub tank 16b via a tube 17. The liquid is stored in the sub tank 16b and the storing tank 16a. The tank 16 is provided corresponding to a number of the liquid discharged or ejected from the nozzles 57; for example, the tank 16 is provided as four tanks 16 corresponding to liquids of four colors (black, yellow, cyan and magenta). With this, the line head 12 discharges or ejects a plurality of kinds of liquids.

In such a manner, the line head 12 is fixed, without being moved, and discharges the liquids from the plurality of nozzles 57. Together with this discharge, the sheet P is conveyed in the conveying direction by the conveyer. With

this, the image is recorded on the sheet P. Note that the foregoing explanation has been made with respect to a case, as an example, in which the liquid discharge heads 13 construct the line head 12. It is allowable, however, that a liquid discharge head 13 may be a serial head, rather than that the liquid discharge heads 13 construct the line head 12.

<Configuration of Liquid Discharge Head>

An explanation will be given about the configuration of each of the liquid discharge heads 13, with reference to FIGS. 3A and 3B. Note that FIG. 3B depicts the cross-sectional structure of the liquid discharge head 13, as depicted in FIG. 3A, as taken along the individual channels (first individual channels 60a and second individual channels 60b which will be described later on). Further, in FIGS. 3A and 3B, a piezoelectric plate which is arranged at a location above a first pressure chamber 50a and a second pressure chamber 50b (to be described later on) and which applies pressure to the liquid inside the first pressure chamber 50a or the second pressure chamber 50b is omitted from the illustration, for the convenience of the explanation.

Respective parts provided on the liquid discharge head 13 can be formed by applying a processing such as the etching (half etching) or machining, etc., with respect to each of a plurality of plates, and by stacking these plates. Alternatively, the respective parts provided on the liquid discharge head 13 may be formed by stacking a plurality of resin plates each of which is molded to have a predetermined shape.

Each of FIGS. 3A and 3B depicts a liquid discharge head 13 in which four different nozzle rows (first nozzle row 100A, a second nozzle row 100B, a third nozzle row 100C and a fourth nozzle row 100D) are arranged. In the present embodiment, the first nozzle row 100A and the second nozzle row 100B are provided on a first island part 300a constructed of a first supply manifold 51a and a first return manifold 52a. Further, the third nozzle row 100C and the fourth nozzle row 100D are provided on a second island part 300b constructed of a second supply manifold 51b and a second return manifold 52b.

In the following, a supply manifold to which the first individual channels 60a connect is referred to as the first supply manifold Ma, a return manifold to which the first individual channels 60a connect is referred to as the first return manifold 52a. Similarly, a supply manifold to which the second individual channels 60a connect is referred to as the second supply manifold Mb, a return manifold to which the second individual channels 60b connect is referred to as the second return manifold 52b. Further, the term "island part" is a unit including a supply manifold and a return manifold which are located to overlap with the pressure chambers provided with the respective individual channels, as seen in a plane view from the nozzle surface. Note that individual channels constructing the first nozzle row 100A provided on the first island part 300a and individual channels constructing the second nozzle row 100B provided on the first island part 300a have a similar configuration. Accordingly, these individual channels are collectively referred to as the "first individual channels 60a". Further, individual channels constructing the third nozzle row 100C provided on the second island part 300b and individual channels constructing the fourth nozzle row 100D provided on the second island part 300b have a similar configuration. Accordingly, these individual channels are collectively referred to as the "second individual channels 60b".

Each of the first individual channels 60a has a first pressure chamber 50a, a first descender 56a which communicates with the first pressure chamber 50a, and a first nozzle 57a which communicates with the first descender 56b and

via which a liquid droplet of the liquid is discharged or ejected. In a case that a side on which the first nozzle **57a** is provided is defined as a down direction or below, and a side opposite to this side is defined as an up direction or above, the first pressure chamber **50a** is provided at a location above the first descender **56a**. A piezoelectric plate (piezoelectric body) is arranged on the upper surface of the first pressure chamber **50a**, and a pressure is applied to the liquid inside the first pressure chamber **50a** by the piezoelectric plate at a predetermined timing. Specifically, in a case that a voltage is applied to the piezoelectric plate at a predetermined timing, the volume of the pressure chamber **50a** having the piezoelectric plate arranged on the upper surface thereof is changed so as to apply the pressure to the liquid inside the first pressure chamber **50a**. With this, it is possible to discharge or eject the liquid droplet from the first nozzle **57a**.

Further, each of the first individual channels **60a** is provided with a first supply throttle part **53a** and is connected to the first supply manifold **Ma** via the first supply throttle part **53a**. Furthermore, each of the first individual channels **60a** is provided with a first return throttle part **54a** and is connected to the first return manifold **52a** via the first return throttle part **54a**. Specifically, the first supply manifold **51a** and the first pressure chamber **50a** of each of the first individual channels **60a** are connected to each other by the first supply throttle part **53a** of which channel diameter is made small. Further, the first nozzle **57a** of each of the first individual channels **60a** and the first return manifold **52a** are connected to each other by the first return throttle part **54a** of which channel diameter is made small.

In the liquid discharge apparatus **1**, the liquid such as the ink, etc., fed from the tank **16** is supplied to the first supply manifold **Ma** via a first inlet port **58a**. The liquid supplied to the first supply manifold **Ma** is supplied to the first pressure chamber **50a** of each of the first individual channels **60a** via the first supply throttle part **53a**. The liquid to which the pressure is applied in the first pressure chamber **50a** flows through the first descender **56a** to be guided to the first nozzle **57a**, and is discharged from the first nozzle **57a** in a state of being the liquid droplet. Here, the liquid which has not been discharged from the first nozzle **57a** is fed to the first return manifold **52a** via the first return throttle part **54a**. The liquid fed to the first return manifold **52a** is returned to the tank **16** via a first outlet port **59a**. In such a manner, each of the first individual channels **60a** provided on the first island part **300a** is configured to perform nozzle circulation. Note that the inside of the first supply manifold **51a** has the normal pressure so as to feed the liquid to the first pressure chamber **50a**. Further, the inside of the first return manifold **52a** has the negative pressure so as to pull thereinto the liquid which has not been discharged from the first nozzle **57a**.

Furthermore, the first supply manifold **51a** and the first return manifold **52a** are arranged to overlap with each other, as seen in a plan view from the nozzle surface in which the first nozzles **57a** are formed. In a case that a side on which the nozzle surface is formed is defined as the down direction or below, and a side opposite to this side is defined as the up direction or above in the liquid discharge head **13**, the supply manifold **51a** is arranged at a location above the first return manifold **52a**. Moreover, a first damper **55a** is provided between the first supply manifold **51a** and the first return manifold **52a**. It is possible to suppress, by the first damper **55a**, any effect of a pressure wave propagated from the first pressure chamber **50a** to the first supply manifold **51a** via the first supply throttle part **53a**. Further, it is also possible

to suppress, by the first damper **55a**, any effect of a pressure wave propagated to the first return manifold **52a** via the first return throttle part **54a**.

Further, each of the second individual channels **60b** also has a configuration similar to that of each of the first individual channels **60a** as described above. Namely, each of the second individual channels **60b** has a second pressure chamber **50b**, a second descender **56b** which communicates with the second pressure chamber **50b**, and a second nozzle **57b** which communicates with the second descender **56b** and via which a liquid droplet of the liquid is discharged or ejected. Further, each of the second individual channels **60b** is connected to the second supply manifold **51b** via a second supply throttle part **53b**, and is connected to the second return manifold **52b** via a second return throttle part **54b**.

Furthermore, the second supply manifold **51b** and the second return manifold **52b** are arranged to overlap with each other, as seen from the nozzle surface, and a second damper **55b** is provided between the second supply manifold **51b** and the second return manifold **52b**. Each of the above-described first damper **55a** and the second damper **55b** is formed of two plates (a first damper plate **80** and a second damper plate **81** in FIG. 4 which will be described later on) in which recessed areas are formed so as to form a damper space. Note that since each of the second individual channels **60b** has a configuration similar to that of each of the first individual channels **60a**, any detailed explanation therefor will be omitted.

Although the first individual channels **60a** and the second individual channels **60b** are different in view of the island parts on which these individual channels are provided, each of the first individual channels **60a** and the second individual channels **60b** has a configuration in which a circulation channel for the liquid is connected thereto by a first bypass channel **70** which will be described later on with reference to FIG. 6. The first supply manifold **51a** and the second return manifold **52b** are connected to each other by the first bypass channel **70**. With this, a part of the liquid inside the first supply manifold **51a** is made to circulate or flow to the second return manifold **52b**. Further, it is possible to realize a manifold circulation between the first supply manifold **51a** and the second return manifold **52b**.

Here, a part of the constituent components of the first bypass channel **70** will be explained by using FIG. 4. Note that the detailed configuration of the first bypass channel **70** will be explained later by using FIGS. 6 and 7.

As depicted in FIG. 4, the part of the constituent elements of the first bypass channel **70** is formed in the first damper plate **80** and the second damper plate **81** constructing the first damper **55a** as described above. The first damper plate **80** and the second damper plate **81** are walls defining or demarcating the first supply manifold **51a** and the second return manifold **52b** from each other. The first damper plate **80** functions also as a plate defining the bottom surface of the first supply manifold **51a**, and the second damper plate **81** functions also as a plate defining the upper surface of the second return manifold **52b**. By cutting off a part of the first damper plate **80**, a first flow channel **70b** as a constituent component of the first bypass channel **70** is provided. The first flow channel **70b** communicates with the inside of the first supply manifold **51a**.

Further, a first connecting channel **70a** is provided by forming a hole penetrating, in the up-down direction, through the second damper plate **81** at an area thereof in which the first damper **55a** and the second damper **55b** are not formed. The first connecting channel **70a** communicates with the inside of the second return manifold **52b** at an end

part thereof, and communicates with the first flow channel 70b at the other end part thereof. The first flow channel 70b is arranged at a position at which the first flow channel 70b overlaps with each of the first supply manifold 51a and the first connecting channel 70a in a case that the first flow channel 70b is seen in a plane view from the nozzle surface.

The first bypass channel 70 can be formed by performing a processing such as the etching or machining with respect to each of the first damper plate 80 and the second damper plate 81 and by stacking the first damper plate 80 and the second damper plate 81. Alternatively, it is allowable that the first damper plate 80 and the second damper plate 81 are resin plates each of which is formed to have a predetermined shape, and that these plates are stacked to thereby form the first bypass channel 70. By appropriately setting the shape and the size of each of the first connecting channel 70a and the first flow channel 70b, it is possible to easily adjust the pressure of the fluid flowing therethrough.

Further, the liquid discharge head 13 has such a configuration that the second supply manifold 51b and the first return manifold 52a are connected to each other by a second bypass channel 71, and that a part of the liquid inside the second supply manifold 51b is made to circulate or flow to the first return manifold 52a. Furthermore, it is possible to realize a manifold circulation between the second supply manifold 51b and the first return manifold 52a.

Here, a part of the constituent components of the second bypass channel 71 will be explained by using FIG. 5. Note that the detailed configuration of the second bypass channel 71 will be explained later by using FIGS. 6 and 7.

As depicted in FIG. 5, the part of the constituent elements of the second bypass channel 71 is formed in the first damper plate 80 and the second damper plate 81 as described above. The first damper plate 80 and the second damper plate 81 are walls defining or demarcating the second supply manifold 51b and the first return manifold 52a from each other. The first damper plate 80 functions also as a plate defining the bottom surface of the second supply manifold 51b, and the second damper plate 81 functions also as a plate defining the upper surface of the first return manifold 52a. By cutting off a part of the first damper plate 80, a second flow channel 71b as a constituent component of the second bypass channel 71 is provided. The second flow channel 71b communicates with the inside of the second supply manifold 51b.

Further, a second connecting channel 71a is provided by forming a hole penetrating, in the up-down direction, through the second damper plate 81 at an area thereof in which the first damper 55a, the second damper 55b and the first bypass channel 70 are not formed. The second connecting channel 71a communicates with the inside of the first return manifold 52a at an end part thereof, and communicates with the second flow channel 71b at the other end part thereof. The second flow channel 71b is arranged at a position at which the second flow channel 71b overlaps with each of the second supply manifold 51b and the second connecting channel 71a in a case that the second flow channel 71b is seen in a plane view from the nozzle surface. Note that the second bypass channel 71 can be formed by a method similar to the method forming the first bypass channel 70 as described above.

In the following, an explanation will be given about the positional relationship among the first supply manifold 51a and the first return manifold 52a constructing the first island part 300a, the second supply manifold 51b and the second return manifold 52b constructing the second island part 300b, and the first bypass channel 70 and the second bypass channel 71, with reference to FIG. 6.

In FIG. 6, the first supply manifold 51a and the second supply manifold 51b are depicted in solid lines, and the first return manifold 52a and the second return manifold 52b are depicted in broken lines. Further, the illustration of the group of the first individual channels 60a and the group of the second individual channels 60b are omitted in FIG. 6.

As depicted in FIG. 6, in a case that, in the liquid discharge head 13 of the present embodiment, the first supply manifold 51a and the first return manifold 52a are seen in a plane view from the nozzle surface, the first supply manifold 51a and the first return manifold 52a are arranged to overlap with each other, and extend in a same direction. The first supply manifold 51a and the first return manifold 52a have lengths in the extending direction (corresponding to the predetermined direction) thereof which are different from each other. Further, in a case that, in the liquid discharge head 13, the second supply manifold 51b and the second return manifold 52b are seen in a plane view from the nozzle surface, the second supply manifold 51b and the second return manifold 52b are arranged to overlap with each other, and extend in a same direction. The second supply manifold 51b and the second return manifold 52b have lengths in the extending direction thereof which are different from each other. From the foregoing description, in the present embodiment, all the first supply manifold 51a, the second supply manifold 51b, the first return manifold 52a and the second return manifold 52b extend in the same extending direction.

A position of a forward end part in the extending direction of the first supply manifold 51a and a position of a forward end part in the extending direction of the second return manifold 52b are at substantially same positions, respectively, and the first bypass channel 70 connects the forward end parts of the first supply manifold 51a and the second return manifold 52b. Further, the first inlet port 58a is provided on the first supply manifold 51a on the side of an end part (referred to as a base end part) thereof which is on the opposite side to the forward end part of the first supply manifold 51a, and the second outlet port 59b is provided on the side of a base end part of the second return manifold 52b.

Furthermore, a position of a forward end part in the extending direction of the second supply manifold 51b and a position of a forward end part in the extending direction of the first return manifold 52a are at substantially same positions, respectively, and the second bypass channel 71 connects the forward end parts of the second supply manifold 51b and the first return manifold 52a. Moreover, the second inlet port 58b is provided on the side of a base part of the second supply manifold 51b, and the first outlet port 59a is provided on the side of a base end part of the first return manifold 52a. In such a manner, in the present embodiment, the first inlet port 58a, the second inlet port 58b, the first outlet port 59a and the second outlet port 59b are arranged on the side of one end in the extending direction.

Further, the first bypass channel 70 is located at a position which is farther from the second bypass channel 71 in the extending direction, and the first bypass channel 70 and the second bypass channel 71 are arranged so as not to overlap with each other. Namely, the second bypass channel 71 is arranged on a side closer to the one end in the predetermined direction (a side on which the respective ports are arranged) than the first bypass channel 70.

In the following, the detailed configuration of each of the first bypass channel 70 and the second bypass channel 71 will be explained. FIG. 7 is an exploded perspective view

depicting the configuration of each of the first bypass channel 70 and the second bypass channel 71.

<Details of First Bypass Channel>

As depicted in FIG. 7, the first bypass channel 70 includes a first supply connecting channel 73 connected to the first supply manifold Ma, a first return connecting channel 70d connected to the second return manifold 52b, and the above-described first connecting channel 70a between the first supply connecting channel 73 and the first return connecting channel 70d. The first supply connecting channel 73 includes the above-described first flow channel 70b and a first supply extended part 70c communicating with the first supply manifold 51a. The first connecting channel 70a is formed, for example, to have a cylindrical shape.

In a state that the respective plates are stacked, the first supply extended part 70c in the plate 90, the first flow channel 70b cut in the first damper plate 80, the first connecting channel 70a penetrating the second damper plate 81 and the first return connecting channel 70d in the plate 91 communicate with one another. With this, the first supply manifold Ma and the second return manifold 52b are allowed to communicate with each other by the first bypass channel 70.

The first flow channel 70b is formed to have, for example, a fan shape. Specifically, the first flow channel 70b has an outer edge e3 having an arc shape curved so as to correspond to an arc-shaped forward end part of the first supply extended part 70c. Further, a forward end part of the first return connecting channel 70d is shaped to curve in an arc form, and has an arc-shaped outer edge e4.

The channel resistance in at least one of the first supply connecting channel 73 and the first return connecting channel 70d is greater than channel resistance in the first connecting channel 70a. In the present embodiment, the channel resistance in the first supply connecting channel 73 and the channel resistance in the first return connecting channel 70d are both greater than the channel resistance in the first connecting channel 70a. Note that the channel resistance in the first supply connecting channel 73 includes at least the channel resistance in the first flow channel 70b. For example, in a case that the viscosity of the ink is 7 cps, the channel resistance in the first supply connecting channel 73 is, for example, in a range of 3.0×10^{11} kg/m⁴·s to 3.5×10^{11} kg/m⁴·s, the channel resistance in the first return connecting channel 70d is, for example, in a range of 1.5×10^{11} kg/m⁴·s to 2.0×10^{11} kg/m⁴·s, and the channel resistance in the first connecting channel 70a is, for example, in a range of 3.0×10^9 kg/m⁴·s to 4.0×10^9 kg/m⁴·s.

Further, the radius of curvature of the outer edge e3 of the first flow channel 70b of the first supply connecting channel 73 is greater than the radius of curvature of the outer edge e4 of the first return connecting channel 70d.

Furthermore, the compliance of the first supply connecting channel 73 is greater than the compliance of the first return connecting channel 70d. Note that the compliance of each of the connecting channels can be obtained by a calculation formula: $Cp = V/c^2 \times p$. Note that in the calculation formula, "V" is the volume of each of the connecting channels, "c" is the acoustic velocity of liquid (acoustic velocity of ink) inside each of the connecting channels, and "p" is the density of liquid (density of ink). The density of ink is, for example, 1054 kg/m³. Further, the acoustic velocity of ink inside each of the connecting channels is, for example, 91 m/s.

In the above-described configuration, the liquid inside the first supply manifold 51a flows into the first flow channel 70b of which opening shape is greater than that of the first

connecting channel 70a. Further, in the first flow channel 70b, the liquid flows toward the position of the end part thereof having the arc shape and overlapping with the first connecting channel 70a. The channel width of the first flow channel 70b is gradually narrowed toward the position of the end part having the arc shape. Accordingly, the magnitude of the pressure of the liquid flowed into the first flow channel 70b is adjusted before the liquid reaches the first connecting channel 70a, and the liquid flows into the second return manifold 52b via the first connecting channel 70a and the first return connecting channel 70d.

<Details of Second Bypass Channel>

Similarly to the first bypass channel 70, the second bypass channel 71 includes a second supply connecting channel 72 connected to the second supply manifold 51b, a second return connecting channel 71d connected to the first return manifold 52a, and the above-described second connecting channel 71a between the second supply connecting channel 72 and the second return connecting channel 71d. The second supply connecting channel 72 includes the above-described second flow channel 71b and a second supply extended part 71c communicating with the second supply manifold 51b. The second connecting channel 71a is formed, for example, to have a cylindrical shape similarly to the first connecting channel 70a, and has a hole diameter which is smaller than a hole diameter of the first connecting channel 70a.

In the state that the respective plates are stacked, the second supply extended part 71c in the plate 90, the second flow channel 71b cut in the first damper plate 80, the second connecting channel 71a penetrating the second damper plate 81 and the second return connecting channel 71d in the plate 91 communicate with one another. With this, the second supply manifold 51b and the first return manifold 52a are allowed to communicate with each other by the second bypass channel 71.

The second flow channel 71b is formed to have, for example, a fan shape. Specifically, the second flow channel 71b has an outer edge e1 having an arc shape curved so as to correspond to an arc-shaped forward end part of the second supply extended part 71c. Further, a forward end part of the second return connecting channel 71d is shaped to curve in an arc form, and has an arc-shaped outer edge e2.

The channel resistance in at least one of the second supply connecting channel 72 and the second return connecting channel 71d is greater than channel resistance in the second connecting channel 71a. In the present embodiment, the channel resistance in the second supply connecting channel 72 and the channel resistance in the second return connecting channel 71d are both greater than the channel resistance in the second connecting channel 71a. Note that the channel resistance in the second supply connecting channel 72 includes at least the channel resistance in the second flow channel 71b.

Further, the radius of curvature of the outer edge e1 of the second flow channel 71b of the second supply connecting channel 72 is greater than the radius of curvature of the outer edge e2 of the second return connecting channel 71d.

Furthermore, the compliance of the second supply connecting channel 72 is greater than the compliance of the second return connecting channel 71d.

In the above-described configuration, the liquid inside the second supply manifold Mb flows into the second flow channel 71b of which opening shape is greater than that of the second connecting channel 71a. Further, in the second flow channel 71b, the liquid flows toward the position of the end part thereof having the arc shape and overlapping with

11

the second connecting channel **71a**. The channel width of the second flow channel **71b** is gradually narrowed toward the position of the end part having the arc shape, in a similar manner regarding the first flow channel **70b**. Accordingly, the magnitude of the pressure of the liquid flowed into the second flow channel **71b** is adjusted before the liquid reaches the second connecting channel **71a**, and the liquid flows into the first return manifold **52a** via the second connecting channel **71a** and the second return connecting channel **71d**.

<Comparison Between First Bypass Channel and Second Bypass Channel>

In the present embodiment, the second bypass channel **71** has the channel resistance which is greater than that of the first bypass channel **70**.

Further, the cross-sectional area of at least one of the first flow channel **70b** of the first supply connecting channel **73** and the first return connecting channel **70d** is greater than the cross-sectional area of the second flow channel **71b** of the second supply connecting channel **72** and the cross-sectional area of the second return connecting channel **71d**. In the present embodiment, the cross-sectional area of the first flow channel **70b** of the first supply connecting channel **73** and the cross-sectional area of the first return connecting channel **70d** are both greater than the cross-sectional area of the second flow channel **71b** of the second supply connecting channel **72** and the cross-sectional area of the second return connecting channel **71d**. Note that as the cross-sectional area of each of the channels, it is possible to adopt the maximum value among the cross-sectional areas of each of the respective channel.

Furthermore, the radius of curvature of at least one of the outer edge **e1** of the second flow channel **71b** of the second supply connecting channel **72** and the outer edge **e2** of the second return connecting channel **71d** is greater than the radius of curvature of the outer edge **e3** of the first flow channel **70b** of the first supply connecting channel **73** and the radius of curvature of the outer edge **e4** of the first return connecting channel **70d**. Moreover, the radius of curvature of at least one of the outer edge **e3** of the first flow channel **70b** of the first supply connecting channel **73** and the outer edge **e4** of the first return connecting channel **70d** is smaller than the radius of curvature of the outer edge **e1** of the second flow channel **71b** of the second supply connecting channel **72** and the radius of curvature of the outer edge **e2** of the second return connecting channel **71d**. In the present embodiment, the radius of curvature of the outer edge **e1** of the second flow channel **71b** of the second supply connecting channel **72** and the radius of curvature of the outer edge **e2** of the second return connecting channel **71d** are greater than the radius of curvature of the outer edge **e3** of the first flow channel **70b** of the first supply connecting channel **73** and the radius of curvature of the outer edge **e4** of the first return connecting channel **70d**.

As explained above, in the liquid discharge head **13** of the present embodiment, the channel resistance in at least one of the first supply connecting channel **73** and the first return connecting channel **70d** is made to be greater than the channel resistance in the first connecting channel **70a**. With this, it is possible to make the difference in the channel resistance in the entire first bypass channel **70** to be substantially absent, even in a case that any deviation in the adhesion among the plates occurs and that a part of the first connecting channel **70a** is clogged. This is similarly applicable also to the second bypass channel **71**. With this, it is possible to allow the liquid to flow from the first supply manifold **51a** to the second return manifold **52b** in the

12

desired flow amount, and to allow the liquid to flow from the second supply manifold **51b** to the first return manifold **52a** in the desired flow amount.

Further, in the present embodiment, the second bypass channel **71** is arranged on the side closer to the one end in the extending direction (the side on which the respective ports are arranged) than the first bypass channel **70**, and has the channel resistance higher than the channel resistance of the first bypass channel **70**. Regarding this point, since the channel resistance in the first bypass channel **70** is high due to that the first bypass channel **70** is at a position which is far from the first inlet port **58a**, the channel resistance in the second bypass channel **71** is made to be great. Due to this, it is possible to make the difference between the resistance in entirety of the first supply manifold **51a**, the first bypass channel **70** and the second return manifold **52b** and the resistance in the entirety of the second supply manifold **51b**, the second bypass channel **71** and the first return manifold **52a** to be small, thereby making it possible to make the flow amount to be same between the respective bypass channels **70** and **71**. Note that the resistance in the entirety of the second bypass channel **71** is, for example, in a range of $4.0 \times 10^{11} \text{ kg/m}^4 \cdot \text{s}$ to $5.0 \times 10^{11} \text{ kg/m}^4 \cdot \text{s}$, and the resistance in the entirety of the first bypass channel **70** is, for example, in a range of $3.0 \times 10^{11} \text{ kg/m}^4 \cdot \text{s}$ to $3.9 \times 10^{11} \text{ kg/m}^4 \cdot \text{s}$,

Furthermore, in the present embodiment, the cross-sectional area of the first flow channel **70b** of the first supply connecting channel **73** and the cross-sectional area of the first return connecting channel **70d** are both greater than the cross-sectional area of the second flow channel **71b** of the second supply connecting channel **72** and the cross-sectional area of the second return connecting channel **71d**. With this, already ensuring the exhaust performance of the air, it is possible to make the difference between the resistance in entirety of the first supply manifold **51a**, the first bypass channel **70** and the second return manifold **52b** and the resistance in the entirety of the second supply manifold **51b**, the second bypass channel **71** and the first return manifold **52a** to be small, with a simple configuration.

Moreover, in the present embodiment, each of the first connecting channel **70a** and the second connecting channel **71a** is formed to have the cylindrical shape. In this configuration, in a case that each of the first connecting channel **70a** and the second connecting channel **71a** has a cross-sectional area which is same as that of a channel having a rectangular cylindrical shape or triangular cylindrical shape, the channel resistance in each of the first connecting channel **70a** and the second connecting channel **71a** is lowered and the liquid is allowed to easily flow therethrough, thereby making it possible to make the liquid to flow in a large flow amount.

Further, in the present embodiment, the hole diameter of the second connecting channel **71a** is smaller than the hole diameter of the first connecting channel **70a**. Due to this, it is possible to make the difference between the resistance in entirety of the first supply manifold **51a**, the first bypass channel **70** and the second return manifold **52b** and the resistance in the entirety of the second supply manifold **51b**, the second bypass channel **71** and the first return manifold **52a** to be small, with a simple configuration. Note that the hole diameter of the second connecting channel **71a** is, for example, in a range of 0.2 mm to 0.3 mm. The channel resistance in the second connecting channel **71a** is, for example, in a range of $1.0 \times 10^9 \text{ kg/m}^4 \cdot \text{s}$ to $2.0 \times 10^9 \text{ kg/m}^4 \cdot \text{s}$. Furthermore, the hole diameter of the first connecting channel **70a** is, for example, in a range of 0.4 mm to 0.5 mm. The channel resistance in the first connecting channel **70a** is, for example, in a range of $3.0 \times 10^9 \text{ kg/m}^4 \cdot \text{s}$ to $4.0 \times 10^9 \text{ kg/m}^4 \cdot \text{s}$.

Further, in the present embodiment, the radius of curvature of the outer edge $e1$ of the second flow channel $71b$ of the second supply connecting channel 72 and the radius of curvature of the outer edge $e2$ of the second return connecting channel $71d$ are greater than the radius of curvature of the outer edge $e3$ of the first flow channel $70b$ of the first supply connecting channel 73 and the radius of curvature of the outer edge $e4$ of the first return connecting channel $70d$. In this configuration, in a case of making the difference in the channel resistance between the respective bypass channels 70 and 71 to be small, the outer edge is longer than the inner edge, and thus the radius of curvature of the outer edge can be adjusted more easily. Furthermore, the air can be easily exhausted toward the respective downstream sides, with the first connecting channel $70a$ and the second connecting channel $71a$ as the references (namely, toward the side of the first return connecting channel $70d$ and the side of the second return connecting channel $71d$).

Moreover, in the present embodiment, the radius of curvature of the outer edge $e3$ of the first flow channel $70b$ of the first supply connecting channel 73 is greater than the radius of curvature of the outer edge $e4$ of the first return connecting channel $70d$. Further, the radius of curvature of the outer edge $e1$ of the second flow channel $71b$ of the second supply connecting channel 72 is greater than the radius of curvature of the outer edge $e2$ of the second return connecting channel $71d$. In this case, a case of adjusting the outer edges on the downstream side (OUT side) of the respective bypass channels 70 and 71 makes it possible to suppress the lowering in the exhaust performance of air, as compared with another case of adjusting the outer edges on the upstream side (IN side) of the respective bypass channels 70 and 71 .

Further, in the present embodiment, the compliance of the first supply connecting channel 73 is greater than the compliance of the first return connecting channel $70d$. Furthermore, the compliance of the second supply connecting channel 72 is greater than the compliance of the second return connecting channel $71d$. Regarding this point, in a case of the configuration wherein an actuator is arranged on the upper side (the side of the pressure chamber) as in the present embodiment, the first and second supply manifolds $51a$ and $51b$, which are close to the actuator, are relatively likely to be greatly affected by the crosstalk by the driving of the actuator. In view of this, by making the compliance of the first supply connecting channel 73 and the compliance of the second supply connecting channel 72 to be relatively great, it is possible to make the effect of the crosstalk to be small as much as possible.

<Modifications>

The present disclosure is not limited to or restricted by the above-described embodiment; a variety of kinds of modifications are possible, within a range not departing from the spirit of the present disclosure, as exemplified as follows.

In the above-described embodiment, the aspect wherein the liquid discharge head 13 is provided with the first supply manifold $51a$, the second return manifold $52b$, the second supply manifold $51b$ and the first return manifold $52a$, as depicted in FIG. 3B. The present disclosure, however, is not limited to this; it is allowable to adopt a liquid discharge head provided with one supply manifold and one return manifold.

As depicted in FIG. 8, a liquid discharge head $13A$ according to a modification is provided with: a supply manifold 200 to which a liquid is supplied from outside; a return manifold 201 from which the liquid is exhausted or discharged to the outside; and a plurality of individual

channels 202 each of which has an upstream end connected to the supply manifold 200 and a downstream end connected to the return manifold 201 , and each of which communicates individually with a one of a plurality of pressure chambers 206 and one of a plurality of nozzles 203 which are aligned to form a row (array) in a nozzle surface. Further, the liquid discharge head $13A$ is provided with a bypass channel 204 connecting the supply manifold 200 and the return manifold 201 with each other. The liquid in the supply manifold 200 flows into each of the plurality of pressure chambers 206 via a supply throttle channel 205 . Such a liquid discharge head $13A$ has a two-story structure wherein the supply manifold 200 is arranged at a location above the return manifold 201 . Note that the liquid which has not been discharged or ejected from the plurality of nozzles 203 flows to the return manifold 201 via a return throttle channel 207 .

The bypass channel 204 includes a supply-side connecting channel $204a$ connected to the supply manifold 200 , a return-side connecting channel $204c$ connected to the return manifold 201 , and a first connecting channel $204b$ between the supply-side connecting channel $204a$ and the return-side connecting channel $204c$. In such a configuration, the channel resistance in at least one of the supply-side connecting channel $204a$ and the return-side connecting channel $204c$ is greater than the channel resistance in the first connecting channel $204b$. In this modification, the channel resistance in the supply-side connecting channel $204a$ and the channel resistance in the return-side connecting channel $204c$ are both made to be greater than the channel resistance in the first connecting channel $204b$.

In such a manner, in the liquid discharge head $13A$ according to the present modification, the channel resistance in the supply-side connecting channel $204a$ and the channel resistance in the return-side connecting channel $204c$ are both made to be greater than the channel resistance in the first connecting channel $204b$. With this, it is possible to make the difference in the channel resistance in the entire first bypass channel 204 to be substantially absent, even in a case that any deviation in the adhesion among the plates occurs and that a part of the first connecting channel $204b$ is clogged. With this, it is possible to allow the liquid to flow from the supply manifold 200 to the return manifold 201 in a desired flow amount.

Further, in the above-described embodiment, in the liquid discharge head 13 as depicted in FIG. 6, the first supply manifold $51a$ and the second supply manifold $51b$ are configured such that the first inlet port $58a$ and the second inlet port $58b$ are provided on the side of the base end parts in the extending direction, of the first supply manifold $51a$ and the second supply manifold $51b$, respectively, which are on the side opposite to the forward end parts in the extending direction of the first supply manifold $51a$ and the second supply manifold $51b$ (at which the first bypass channel 70 and the second bypass channel 71 are provided, respectively). Furthermore, the first return manifold $52a$ and the second return manifold $52b$ are also configured such that the first outlet port $59a$ and the second outlet port $59b$ are provided on the side of the base end parts in the extending direction, of the first return manifold $52a$ and the second return manifold $52b$, respectively, which are on the side opposite to the forward end parts in the extending direction of the first return manifold $52a$ and the second return manifold $52b$. The positions in each of which one of the first inlet port $58a$, the second inlet port $58b$, the first outlet port $59a$ and the second outlet port $59b$ is provided in not limited to being on the base end part in the extending direction. It is allowable that the first inlet port $58a$, the second inlet port

15

58b, the first outlet port **59a** and the second outlet port **59b** are provided respectively on the first supply manifold Ma, the second supply manifold Mb, the first return manifold **52a** and the second return manifold **52b**, at ends parts, respectively, which are on different sides in the extending direction thereof. It is allowable that the first inlet port **58a**, the second inlet port **58b**, the first outlet port **59a** and the second outlet port **59b** are provided arbitrarily, depending on the arrangement or the shape of a channel (not depicted in the drawings) in which the liquid is supplied to the first supply manifold **51a** via the first inlet port **58a** and to the second supply manifold **51b** via the second inlet port **58b** and is allowed to flow, and the arrangement or the shape of a channel (not depicted in the drawings) in which the liquid is exhausted or discharged from the first return manifold **52a** via the first outlet port **59a** and from the second return manifold **52b** via the second outlet port **59b**.

Moreover, in the above-described embodiment, the channel resistance in the first supply connecting channel **73** and the channel resistance in the first return connecting channel **70d** are both made to be greater than the channel resistance in the first connecting channel **70a**. The present disclosure, however, is not limited to this. It is allowable that either one of the channel resistance in the first supply connecting channel **73** and the channel resistance in the first return connecting channel **70d** is made to be greater than the channel resistance in the first connecting channel **70a**.

Further, in the above-described embodiment, the channel resistance in the second supply connecting channel **72** and the channel resistance in the second return connecting channel **71d** are both made to be greater than the channel resistance in the second connecting channel **71a**. The present disclosure, however, is not limited to this. It is allowable that either one of the channel resistance in the second supply connecting channel **72** and the channel resistance in the second return connecting channel **71d** is made to be greater than the channel resistance in the second connecting channel **71a**.

Furthermore, in the above-described embodiment, the cross-sectional area of the first flow channel **70b** of the first supply connecting channel **73** and the cross-sectional area of the first return connecting channel **70d** are both made to be greater than the cross-sectional area of the second flow channel **71b** of the second supply connecting channel **72** and the cross-sectional area of the second return connecting channel **71d**. The present disclosure, however, is not limited to this. It is allowable that at least one of the cross-sectional area of the first flow channel **70b** of the first supply connecting channel **73** and the cross-sectional area of the first return connecting channel **70d** is made to be greater than the cross-sectional area of the second flow channel **71d** of the second supply connecting channel **72** and the cross-sectional area of the second return connecting channel **71d**.

Moreover, in the above-described embodiment, the radius of curvature of the outer edge e1 of the second flow channel **71b** of the second supply connecting channel **72** and the radius of curvature of the outer edge e2 of the second return connecting channel **71d** are made to be greater than the radius of curvature of the outer edge e3 of the first flow channel **70b** of the first supply connecting channel **73** and the radius of curvature of the outer edge e4 of the first return connecting channel **70d**. The present disclosure, however, is not limited to this. It is allowable that the radius of curvature of either one of the outer edge e1 of the second flow channel **71b** of the second supply connecting channel **72** and the outer edge e2 of the second return connecting channel **71d** is made to be greater than the radius of curvature of the outer

16

edge e3 of the first flow channel **70b** of the first supply connecting channel **73** and the radius of curvature of the outer edge e4 of the first return connecting channel **70d**.

What is claimed is:

1. A liquid discharge head comprising:
a plurality of first individual channels, each of the first individual channels including a first nozzle;
a first supply manifold connected to the plurality of first individual channels and configured to supply a liquid to the plurality of first individual channels;
a first return manifold connected to the plurality of first individual channels and configured to cause the liquid not discharged from the first nozzle to flow therein;
a plurality of second individual channels, each of the second individual channels including a second nozzle;
a second supply manifold connected to the plurality of second individual channels and configured to supply the liquid to the plurality of second individual channels;
a second return manifold connected to the plurality of second individual channels and configured to cause the liquid not discharged from the second nozzle to flow therein; and
a first bypass channel connecting the first supply manifold and the second return manifold,
wherein the first bypass channel includes: a first supply connecting channel connected to the first supply manifold; a first return connecting channel connected to the second return manifold; and a first connecting channel communicating the first supply connecting channel and the first return connecting channel, and
wherein channel resistance in one of the first supply connecting channel and the first return connecting channel is greater than channel resistance in the first connecting channel.

2. The liquid discharge head according to claim 1, further comprising:

a first inlet port configured to cause the liquid to flow therethrough and into the first supply manifold;
a second inlet port configured to cause the liquid to flow therethrough and into the second supply manifold;
a first outlet port configured to cause the liquid to flow therefrom and out from the first return manifold;
a second outlet port configured to cause the liquid to flow therefrom and out from the second return manifold; and
a second bypass channel connecting the second supply manifold and the first return manifold,
wherein the first supply manifold, the second supply manifold, the first return manifold and the second return manifold extend in a first direction,
wherein the first inlet port, the second inlet port, the first outlet port and the second outlet port are arranged on a side of one end in the first direction, and
wherein the second bypass channel is arranged on a side closer to the one end in the first direction than the first bypass channel, and channel resistance in the second bypass channel is greater than channel resistance in the first bypass channel.

3. The liquid discharge head according to claim 2, wherein the second bypass channel includes: a second supply connecting channel connected to the second supply manifold; a second return connecting channel connected to the first return manifold; and a second connecting channel communicating the second supply connecting channel and the second return connecting channel, and

wherein a cross-sectional area of one of the first supply connecting channel and the first return connecting channel is greater than a cross-sectional area of the

17

second supply connecting channel and a cross-sectional area of the second return connecting channel.

4. The liquid discharge head according to claim 3, wherein the first connecting channel of the first bypass channel and the second connecting channel of the second bypass channel have a cylindrical shape.

5. The liquid discharge head according to claim 3, wherein a hole diameter of the second connecting channel of the second bypass channel is smaller than a hole diameter of the first connecting channel of the first bypass channel.

6. The liquid discharge head according to claim 3, wherein a radius of curvature of an outer edge of one of the second supply connecting channel and the second return connecting channel is greater than a radius of curvature of an outer edge of the first supply connecting channel and a radius of curvature of an outer edge of the first return connecting channel.

7. The liquid discharge head according to claim 3, wherein a radius of curvature of an outer edge of one of the first supply connecting channel and the first return connecting channel is smaller than a radius of curvature of an outer edge of the second supply connecting channel and a radius of curvature of an outer edge the second return connecting channel.

8. The liquid discharge head according to claim 3, wherein a radius of curvature of an outer edge of the first supply connecting channel is greater than a radius of curvature of an outer edge of the first return connecting channel, and

30 wherein a radius of curvature of an outer edge of the second supply connecting channel is greater than a radius of curvature of an outer edge the second return connecting channel.

18

9. The liquid discharge head according to claim 3, wherein the first supply manifold is arranged at a location above the first return manifold,

5 wherein the second supply manifold is arranged at a location above the second return manifold;

wherein compliance of the first supply connecting channel is greater than compliance of the first return connecting channel, and

10 wherein compliance of the second supply connecting channel is greater than compliance of the second return connecting channel.

10. A liquid discharge head comprising:

a supply manifold configured to cause a liquid to be supplied thereto from outside;

a return manifold configured to cause the liquid to be exhausted therefrom to the outside;

15 a plurality of individual channels, each of the individual channels including an upstream end connected to the supply manifold and a downstream end connected to the return manifold, and each of the individual channels communicating individually with one of a plurality of nozzles arranged in a row on a nozzle surface; and a bypass channel connecting the supply manifold and the return manifold,

wherein the bypass channel includes: a supply connecting channel connected to the supply manifold; a return connecting channel connected to the return manifold; and a connecting channel connecting the supply connecting channel and the return connecting channel, and 20 wherein channel resistance in one of the supply connecting channel and the return connecting channel is greater than channel resistance in the connecting channel.

* * * * *
